WELL JARRING TOOL

Thomas A. Andrew, Newport Beach, Calif.

Application August 22, 1955, Serial No. 529,759

6 Claims. (Cl. 255—27)

This invention relates generally to well drilling apparatus and more particularly to jarring tools.

In the drilling and maintenance of wells, such as oil wells, it is frequently necessary to loosen drill strings or other items of drilling equipment that have become fast in the well bore. These items are commonly referred to as "fish."

According to one procedure for removing the fish, a fishing string, including a jar, is run into the bore and attached to the fish by means of a spear or overshot. A strain is then taken on the string and the latter, owing to its elasticity and length, is stretched a substantial amount. At a predetermined pull on the string, mechanism within the jar is released and the elasticity of the stretched drill string provides a force which accelerates the mass of the drill pipe upwardly. Upward movement of the string is arrested by engagement of a hammer, carried on the string, with an anvil to produce an impact of substantial intensity which tends to loosen the fish.

Existing jars of this type are, however, deficient in that in the interval between release of the mechanism and engagement of the hammer with the anvil, the section of the string extending between the jar and fish, through which the impact is transmitted to the fish, is momentarily released to drop downwardly in the well bore so that the strain on this section and on the fish is relieved. The effectiveness of the subsequent impact of the jar is, therefore, diminished to the extent of the energy required to restore this strain.

Further, the hammer of such jars is rigidly fixed to the drill pipe so that the impact acts equally on the drill pipe above the jar and surface equipment as well as on the drill pipe below the jar and the fish. Inasmuch as in certain wells only relatively light pipe is available for such jarring operations, the intensity of the blow which may be struck is severely restricted by the ability of the pipe to withstand the impacts. Also the transmission of high intensity impacts to the surface occasioned by the use of these jars often results in damage to the drill rig and injury to operating personnel.

It has been determined that the type of blow which is most effective in removing a fish varies with the different conditions under which an object may become stuck in a well bore. For example, where a fish is held in a sand formation, a series of rapid sharp blows, or impacts of short duration, are the most effective.

Since, in existing jars, the hammer is rigid on the drill string, the mass of the hammer is combined with that of the string, and owing to the substantial mass involved, short duration impacts cannot be produced.

Various types of so-called hammer jars have been developed in an attempt to produce sharper impacts and to restrict the latter to the fish. Generally, these hammer jars embody a separate hammer of relatively small mass which is movable with respect to the drill string and which is depressed against the action of a spring by mechanism operated by rotation of the drill string. Upon being released, as by a strain being taken in the string,

2

the hammer is driven by the spring into impact with an anvil to produce a sharp impact that is transmitted mainly to the fish and substantially isolated from the drill string extending to the surface. This type of hammer jar is effective in those situations requiring sharp blows but is limited in its application owing to the necessity of rotating the drill string to reset the hammer and by the fact that only relatively small springs can be housed within a jar so that the intensity of the impact is severely restricted.

A broad object of this invention is the provision of jarring tools which avoid the above and other deficiencies of existing jars.

A more specific object of the invention is the provision of a well jar which is effective to deliver relatively high intensity impacts of short duration mainly to the fish and away from the surface and which operates to maintain a strain on the fish during the jarring operation.

Another object of the invention is the provision of a hammer-type well jar wherein the impacts produced are substantially isolated from the surface equipment so that blows of greater intensity may be safely produced.

Still another object of the invention is the provision of a hammer-type well jar which, while producing relatively high intensity impacts, may be run on light tubing or cable.

Yet another object is the provision of a hammer-type jar wherein an initial strain may be taken on the fish and maintained during movement of the hammer into impact with the anvil and wherein resetting of the hammer is accomplished without rotation of the drill string or releasing of the initial strain on the fish.

A further object of the invention is the provision of a jarring tool which may be run with a conventional straight pull jar for increasing the effectiveness and reducing the surface impact of the conventional jar.

Yet a further object is the provision of a booster jar to be run with a conventional jar which operates to produce an impact so synchronized with the impact of the conventional straight pull jar for increasing the effectiveness and reducing the surface impact of the conventional jar.

Yet a further object is the provision of a booster jar to be run with a conventional jar which operates to produce an impact so synchronized with the impact of the conventional or basic jar as to occur after the impact of the basic jar has restored the initial strain on the fish.

According to one illustrative embodiment of the invention, the jar embodies a mandrel which at its upper end is adapted for rigid attachment to a drill string extending to the surface and which slidably mounts a hammer that normally bears against an upwardly facing shoulder of the mandrel. The lower end of the mandrel is telescoped into the upper end of a cylindrical casing having a downwardly facing anvil surface and is retained in a lower position in the casing by releasable detent mechanism or latching means. Springs bias the mandrel to its lower position in the casing and the hammer downwardly on the mandrel into abutment with the mandrel shoulder.

When the jar is run on a fishing string and a strain is taken on the string, the latter will stretch until, at a predetermined pull, the latching means release. The restoring force developed by stretching of the string will accelerate the mass of the string and also the hammer, due to its abutment with the mandrel shoulder, upwardly. The hammer is moved upwardly on the mandrel into impact with the anvil surface while the energy of the upwardly moving mandrel and drill pipe attached thereto will be relatively gradually absorbed by the mandrel biasing spring so that substantially no impact is transmitted through the fishing string to the surface. The strength of the mandrel biasing spring is made such that the man-

mandrel may be re-engaged with the detent mechanism without lowering, below a desired value, the strain on the fish. Also the hammer, following its initial high intensity impact will rebound several times between the anvil surface and mandrel shoulder to produce a series of sharp blows.

A modified form of the invention, hereinafter referred to as a booster jar, is similar in construction to the jar just described differing only in the omission of the detent mechanism so that except for the restraining force of its biasing spring, the mandrel is free to move in the casing.

This booster jar is run in a fishing string with any conventional, or basic, jar which, as hereinbefore described, permits momentary release of the strain on the fish. The arrangement of the booster jar is such that it will impart a series of sharp blows which are so synchronized with the impact of the basic jar as to occur after the initial strain on the fish has been regained by the basic jar.

A better understanding of the invention may be had from the following detailed description thereof taken in conjunction with the annexed drawings wherein:

Fig. 1 is a longitudinal section through a well bore casing and a fishing string therein incorporating one form of the jar of this invention, the parts of the jar being shown in their normal positions;

Fig. 2 is a view similar to Fig. 1 but with the parts of the jar shown at the instant of impact;

Fig. 3 is a section taken along line 3—3 of Fig. 1;

Fig. 4 is a section taken along line 4—4 of Fig. 1;

Fig. 5 is a longitudinal section through a modified form of jar, the parts thereof being shown in their normal positions;

Fig. 6 is a view similar to Fig. 5 but with the parts of the jar shown at the instant of impact; and

Figs. 7 and 8 are views illustrating two ways of placing the jar of Figs. 5 and 6 in a fishing string.

Referring first to Figs. 1—4 of the drawings, the hammer jar 20 of the invention comprises a mandrel 21 which has its upper end enlarged at 22 and formed with a coupling box 23 for connection to a coupling pin 24 on the lower end of a string of drill pipe 25 extending to the surface. The lower end of mandrel 21 has a pair of axially spaced enlargements 26 and 26' defining an annular groove 27 therebetween. Intermediate the enlargements 22 and 26, the mandrel is formed with an integral annular abutment 28 and slidable on the mandrel between this abutment and enlargement 22 is a hammer 29.

The hammer has a reduced diameter lower end portion 30 terminating in an enlarged shoulder 31 whose upper annular face 32 forms the striking face of the hammer. A compression spring 33 encircles mandrel 21 and abuts at one end enlargement 22 and at the other end hammer 29 so that the latter is biased downwardly on the mandrel into engagement with abutment 28.

Telescoped over the lower end portion of the mandrel and lower portion 30 of the hammer is an anvil sleeve 34. The peripheral surface of hammer shoulder 31 slidably engages the inner cylindrical surface 35 of the sleeve and the upper end of the latter is extended radially inwardly to form an annular shoulder 36 whose inner cylindrical surface slidably engages the end portion 30 of the hammer. The lower annular face 37 of the shoulder 36 forms an anvil face against which hammer face 32 is adapted to strike, as will presently be seen.

In the normal position of the mandrel, hammer, and anvil sleeve, as illustrated in Fig. 1, head 31 of the hammer abuts an annular shoulder 38 in the sleeve, spaced a distance below anvil face 37, and abutment 28 of the mandrel rests on a further annular shoulder 39. A second compression spring 40, encircling the mandrel and bearing at one end against the lower face of shoulder 39 and at the other end against enlargement 26' of the mandrel, biases the latter downwardly in sleeve 34 to said normal position.

Mounted in four equi-angularly spaced axial slots 41

(see Fig. 3) in the outer surface of the sleeve 34, and fixed at opposite ends to the latter, are four spring bars 42. Intermediate the ends of the bars are integral detents 43 which extend through openings 44 in the wall of the sleeve and project into annular groove 27 of the mandrel. The corners of these detents are beveled, as indicated at 45, and the lower end of the mandrel is peripherally beveled at 46 to provide for camming of the detents into and out of the mandrel groove 27 during operation of the jar, to be presently described.

The lower end of anvil sleeve 34 is formed with a coupling pin 47 adapted for securement in a coupling box 48 in the upper end of a string of drill pipe 49 extending to the fish. In a fishing operation, the lower end of section 49 is rigidly attached, in any conventional manner, as by a spear or overshot, not shown, to the fish to be retrieved.

A passage 50 may extend axially through the drill strings 25, 49 and the mandrel 21 to provide for the flow 20 of mud or other fluid to the fish during jarring operations to facilitate loosening of the fish.

In use, the jar 20 is assembled in the fishing string 25, 49 and the latter is lowered into the casing 51 of a well bore and attached, as previously mentioned, to the fish by a spear or overshot, not shown. A strain is then taken on the drill pipe at the surface, the mandrel and anvil sleeve being locked against relative movement by detents, or latching means, 43. As the pull on the drill string is increased, the drill pipe will stretch, and after 30 the pull attains a predetermined value, which may be varied by changing the strength of the spring bars 42, the latching means 43 will be cammed out of the mandrel groove 27 resulting in outward bowing of the spring bars, as illustrated in Fig. 2.

Upon release of the mandrel from the anvil sleeve, the tensile forces produced by stretching of the drill pipe 25 will upwardly accelerate the mass of the pipe, and also hammer 29 due to its engagement with mandrel abutment 28. Upward movement of the mandrel in the sleeve 34 will be relatively gradually arrested by compressing of the mandrel biasing spring 40 so that the energy of the upwardly moving mass of drill pipe will be absorbed over a relatively extended period of time. Thus, substantially no impact will be delivered to the drill pipe 25 and transmitted therethrough to the surface.

Hammer 29 is, however, substantially freely slidable along the mandrel and its upward movement is suddenly arrested by engagement with the anvil face 37. The resulting impact is transmitted through sleeve 34, and drill pipe 49 to the fish.

At the upper limit of movement of mandrel 21 in sleeve 34 (Fig. 2), the upper face of mandrel abutment 28 will be spaced from anvil face 37 a distance which is slightly greater than the axial dimension of hammer shoulder 31, and the hammer, after its initial impact with the anvil 37 will rebound back and forth between the abutment and anvil to impart a series of rapid, sharp blows to the fish.

Hammer biasing spring 33 has a relatively low spring 60 constant inasmuch as its function is merely that of returning the hammer to its normal position in contact with abutment 28 on the mandrel. Mandrel biasing spring 40 has a relatively high spring constant since one of its 65 functions is that of arresting the upward movement of the relatively great mass of the mandrel and drill pipe.

The mandrel biasing spring serves the additional, highly important function of preventing complete release of the strain on the fish after disengagement of the detents 43. To this end, the spring 40, in its normal expanded condition, illustrated in Fig. 1, will be tensed in accordance with the minimum strain to be maintained on the fish. Thus, while the strain on the fish will, after release of the latching means, decrease substantially below the relatively high value of strain taken in the drill

String to release the latching means, it will not drop below the initial tension in the mandrel biasing spring.

In resetting the jar, the strain on the drill string is relieved sufficiently to allow the mandrel biasing spring to return the mandrel to its normal position, of Fig. 1, wherein the detents are received in the groove 27. The bevel corners 45 of the detents and beveled bottom edge 46 of the mandrel cause outward camming of the detents as the mandrel is moved downwardly in the anvil sleeve 34 by its biasing spring 40 so that the detents will ride over the surface of the enlargement 26 and drop into the groove 27. The above described cycle is repeated as many times as is necessary to remove the fish.

Referring next to Figs. 5-8, there is illustrated a booster jar 20' which may be run with any conventional basic jar 52 for supplementing the impact of the basic jar. Conventional, straight pull jars have the previously noted deficiency of relieving the strain on the fish during travel of the hammer into impact with the anvil following tripping of the release mechanism within the jar.

Booster jar 20' is substantially identical with the jar of Figs. 1-4 differing therefrom only by the omission of the latching means including spring bars 42, detents 43, and groove 27 in the mandrel. It will be seen, therefore, that except for the biasing action of the mandrel biasing spring 40', the mandrel 21' of the booster jar is freely movable in the anvil sleeve 34'.

In use, the booster jar is run either below the basic jar 52, as illustrated in Fig. 7, or above the basic jar, as illustrated in Fig. 8. The basic jar 52 may be any conventional jar which delivers an impact when a hammer in the jar is released upon a predetermined strain being taken in the fishing string 53. The mandrel biasing spring 40', in its normal expanded condition shown in Fig. 5, has an initial tension such that it will be only partially compressed when a strain is taken in the drill pipe to release the hammer in the basic jar so as to allow for movement of the booster hammer 29'.

A relatively light hammer biasing spring 33' is provided, as in first described jar, for returning the hammer to its normal position against the mandrel abutment 28'.

Assume first that the booster is run above the basic jar 52, as illustrated in Fig. 8. Under these conditions, when the strain is taken in the drill pipe to release the basic jar, the mandrel biasing spring 40' is partially compressed, as just mentioned, and the booster hammer 29' is spaced from the anvil 37'. When the basic jar releases, the section of drill pipe above the basic jar, in which the booster is connected, moves upwardly under the action of the tension in the drill pipe. This upward travel of the section of drill pipe between the booster and basic jar, and the anvil sleeve 34' of the booster, which is connected to the section, is suddenly arrested by engagement of the impact surfaces in the basic jar. Upward travel of the mandrel 21' is immediately thereafter arrested by the mandrel biasing spring 40', the tension in which is momentarily relieved during the interval between the release and subsequent impact of the basic jar.

This impact of the basic jar and the inertia of the hammer 29' cause the latter to strike the now arrested anvil 37', rebound, and then strike the anvil again to produce a series of rapid impacts, as in the previous form of the jar. These impacts of the booster occur after the impact of the basic jar. The impacts of the basic jar, as well as the subsequent impact of the booster jar, are effectively isolated from the section of drill pipe above the booster by the mandrel spring 40'.

Assume now that the booster is run below the basic jar, as illustrated in Fig. 7. Under these conditions, when the basic jar releases, the section of drill pipe below the basic jar, and therefore the booster, move downwardly under the combined action of gravity and the tension in the latter section of drill pipe. This downward travel of the pipe section and the mandrel 21' connected thereto

is suddenly arrested by engagement of the impact surfaces of the basic jar. The anvil sleeve 34', however, and the section of drill pipe therebelow, continue to move downwardly. As in the arrangement of Fig. 8, the mandrel biasing spring 40' is slightly relieved and thereby expands during the interval between release and subsequent impact of the basic jar.

The impact of the basic jar is transmitted through the lower section of drill pipe and mandrel to the mandrel shoulder 28'. This impact tends to impel the hammer 29' toward the anvil 37'. This action, in combination with the continued downward travel of the anvil sleeve 34', after arresting of the mandrel 28', results in engagement of the hammer 21' with the anvil to produce a series of rapid impacts after the impact of the basic jar. Downward movement of the anvil sleeve 34' is arrested by compression of the mandrel biasing spring.

As previously described, the basic jar, in striking its blow, releases tension in the drill pipe extending from the jar to the fish. A substantial portion of the energy of impact of the jar is, accordingly, expended in regaining this tension and in lifting the fish to its original position if it drops slightly during the release of tension thereon. The effect of the impact in removal of the fish is thus lessened.

The present booster jar when run with the basic jar, however, becomes operative to deliver its series of sharp impacts to the fish only after the strain on the latter has been regained. Thus, it will be clear from what has just been said that the decrease in the upward strain on the fish, which occurs immediately after release of the basic jar, is regained upon engagement of the striking surfaces of the basic jar to produce an impact. This upward strain is transmitted through the mandrel biasing spring of the booster which is initially pretensed, as previously mentioned. Immediately upon engagement of the striking surfaces of the basic jar, of course, the tension in the biasing spring increases to increase the upward strain on the fish. As mentioned above, the booster impact occurs after the impact of the basic jar. The booster impacts will, therefore, be synchronized with the basic jar impact to occur after the basic jar impact has regained the tension on the fish. These sharp, booster jar impacts delivered to the fish while a strain is taken thereon, intensify the impact of the basic jar and have maximum effectiveness in loosening the fish.

If the booster jar 20' is run below the basic jar 52, as illustrated in Fig. 7, its impacts will have maximum efficiency due to its immediate proximity to the fish, not shown.

If the booster jar is run above the basic jar, as illustrated in Fig. 8, it will tend to render the impact of the basic jar more effective and will substantially eliminate the transmissions of the basic jar impacts to the surface since it, in effect, isolates the basic jar from the drill pipe extending to the surface. In either position, the booster jar will have the effect of delivering to the fish a series of sharp blows while a strain is being exerted thereon.

While I have shown and described certain preferred forms of my invention, it will be understood that they are merely illustrative in nature and that various changes may be made in the design and arrangement of parts of the invention without departing from the spirit and scope of the following claims.

I claim:

1. A well jarring tool to be run in a fishing string, comprising: a pair of telescopic members having coupling means at their free ends for connection of the jar in a fishing string, a hammer slidably mounted on one member for axial movement relative to both members, said hammer having a striking surface facing the free end of said one member, an anvil on the other member having an impact surface facing the free end of said other member and located between said striking surface and

the free end of said one member, said impact surface being engageable by the hammer surface to produce an impact by axial movement of the hammer toward the free end of said one member, rigid shoulder means on said one member engageable with the hammer for limiting axial movement of the latter away from the free end of said one member, yieldable means biasing said members toward one another to a given normal position, wherein said hammer is spaced from the anvil, said hammer being relatively moved toward said anvil by said shoulder means when said members are moved apart.

2. A well jarring tool to be run in a fishing string, comprising: a pair of telescopic members having coupling means at their free ends for connection of the jar in a fishing string, releasable latch means carried on the members for retaining the latter in a given normal position relative to one another and against axial movement under axial forces of less than a predetermined value applied to the members tending to separate the latter, said latch means being released to permit axial movement of the members in directions away from one another in response to axial forces exceeding said predetermined value, a hammer axially movable relative to both members, means defining an anvil on one of the members engageable by the hammer to produce an impact by axial movement of the hammer away from the free end of said one member, rigid shoulder means on the other member engageable with the hammer for limiting axial movement of the latter away from the free end of said other member, said hammer being spaced from the anvil when said members are in said normal relative position and being relatively moved toward said anvil by said shoulder means when said members are moved apart, and yieldable means acting between said members for biasing the latter to said normal relative position.

3. The subject matter of claim 1 wherein said yieldable means comprises a coil compression spring having such a spring constant as to resiliently arrest axial separation of the members to a position wherein said hammer is capable of limited axial movement between said anvil and shoulder means.

4. The subject matter of claim 1 including relatively light spring means acting between said one member and hammer for biasing the latter toward said shoulder means.

5. A well jarring tool to be run in a fishing string, comprising: a pair of generally tubular, telescopic members, coupling means on the free ends of said members for connection of the jar in a fishing string, a tubular hammer slideably mounted on the inner one of said members and having one end slideably received within the inner end of the outer member, said inner end of the outer mem-

ber having an inwardly extending flange defining an anvil face and said one end of the hammer having an outwardly extending flange defining a hammer face engageable with said anvil face to produce an impact by axial movement of the hammer away from the free end of the outer member, a shoulder on said inner member engageable with the hammer for limiting axial movement of the latter toward the inner end of the inner member, spring means acting between said members for biasing the latter toward one another to a given normal position wherein said hammer face is spaced from said anvil face and resiliently arresting axial separation of the members prior to engagement of said hammer and anvil faces.

6. A well jarring tool to be run in a fishing string, comprising: a pair of generally tubular, telescopic members, coupling means on the free ends of said members for connection of the jar in a fishing string, a tubular hammer slideably mounted on the inner one of said members and having one end slideably received within the inner end of the outer member, said inner end of the outer member having an inwardly extending flange defining an anvil face and said one end of the hammer having an outwardly extending flange defining a hammer face engageable with said anvil face to produce an impact by axial movement of the hammer away from the free end of the outer member, a shoulder on said inner member engageable with the hammer for limiting axial movement of the latter toward the inner end of the inner member, cooperating releasable latch means on said members for retaining the latter in a given normal position relative to one another under axial forces of less than a predetermined value applied to the members tending to separate the latter, said latch means being released to permit axial movement of the members in directions away from one another in response to axial forces exceeding said predetermined value, said hammer face being spaced from said anvil face when the members are in said normal relative position, and spring means acting between said members for biasing the latter to normal position and resiliently arresting axial separation of the members prior to engagement of said hammer and anvil faces after release of said latch means.
